BLIND STITCH MACHINE

Anthony Greco, Hasbrouck Heights, N. J.

Application May 23, 1951, Serial No. 227,883

7 Claims. (Cl. 112—178)

1

This invention relates to sewing especially to sewing by machine and more particularly to blind-stitch sewing of two layers of material together at separated positions and blind-stitch sewing of buttons to material.

A principal object of this invention is to produce a sewing machine of such construction that material to be sewed together at separated positions will be positively and properly held firmly in one position while being sewed together and a button and material to which it is to be sewed will be held firmly, positively and properly while the button is being sewed to the material.

A further object of this invention is to produce a machine of the type specified so constructed that the holding means for materials and buttons may be easily and quickly manipulatable to hold and also to release the materials and button.

A further object of the invention is to produce a machine of the type specified which will embody a tension mechanism for the thread used in sewing so constructed that a proper and efficient tension will be maintained for the type of sewing done.

Other objects and advantages will appear as the description of the particular physical embodiment selected to illustrate the invention progresses and the novel features will be particularly pointed out in the appended claims.

In describing the invention in detail and the particular physical embodiment selected to illustrate the invention, reference will be had to the accompanying drawings and the letters and figures of reference thereon, in which:

Figure 1 is a top plan view of a machine embodying my invention; Fig. 2 is a fragmentary end elevational view of the device as shown by Fig. 1 viewed in the direction of the arrow A; Fig. 3 is a fragmentary cross sectional view of the device, as shown by Fig. 2, on the plane indicated by the line III—III viewed in the direction of the arrows at the ends of the line; Fig. 4 is a fragmentary cross sectional view of the device as shown by Fig. 3 on the plane indicated by the line IV—IV viewed in the direction of the arrows at the ends of the line; Fig. 5 is a fragmentary cross sectional view of the device as shown by Fig. 4 on the plane indicated by the line V—V viewed in the direction of the arrows at the ends of the line; Fig. 6 is a fragmentary top plan view, with some parts broken away, illustrating the positioning of a material and a button to be sewed thereto; Fig. 7 is a view similar to Fig. 3 but illustrating the application of a tacking fitting; Fig. 8 is a fragmentary cross

2

sectional view of the device as shown by Fig. 7 on the plane indicated by the line VIII—VIII viewed in the direction of the arrows at the ends of the line; Fig. 9 is a view similar to Fig. 6 but illustrating the arrangement of a tacking fitting; Fig. 10 is a perspective view of a tacking fitting of my invention; Fig. 11 is a perspective view of a wear plate of my invention; Fig. 12 is a plan view of a material and a label tacked thereto; Fig. 13 is a fragmentary view illustrating the position of thread, needle, and materials when tacking is performed; Fig. 14 is a view similar to Fig. 13 but illustrating the tacking of a label or the like to material; Fig. 15 is a fragmentary cross sectional view of the device as shown by Fig. 2 on the plane indicated by the line XV—XV viewed in the direction of the arrows at the ends of the line; Figs. 16 to 21, inclusive, illustrate the operation of a machine of my invention in attaching a cloth shank button to material; Fig. 22 illustrates a fragment of material and a button attached thereto as the result of the operations illustrated by Figs. 16 to 21 inclusive; Fig. 23 illustrates the opposite side of material to which a button is attached; Fig. 24 illustrates a button receiver; Fig. 25 is a fragmentary plan view of the needle plate arranged to cooperate with a button having an eyelet shank; Fig. 26 is a fragmentary cross sectional view of the device as shown by Fig. 25 on the plane indicated by the line XXVI—XXVI viewed in the direction of the arrows at the ends of the line illustrating the attaching of a button with an eyelet shank; Fig. 27 is a perspective view of a button with an eyelet shank suitable for attachment by my device; Fig. 28 is a perspective view of a button with a textile material shank suitable for attachment by my device.

For the purpose of illustration, the invention is shown in the accompanying drawings as embodied in a blind-stitch sewing machine of the general type illustrated in the United States patents to C. A. Dearborn, Nos. 679,553, 705,325, 705,326 and 814,025.

In general the machine comprises a main frame or longitudinal arm B, Fig. 1, which extends horizontally from substantially one end of the machine to the other. This arm B is supported at the right hand end, as viewed in Fig. 1, by a base frame C.

At the left of the arm B, as viewed in Fig. 1, a transverse arm D projects forwardly, at substantially a right angle to arm B, to about the position of the stitch forming mechanism, denoted generally by S.

The main drive shaft 1, is journalled in arm B. This drive shaft extends the length of B and protrudes at each end.

At the right hand end, as viewed in Fig. 1, the shaft is provided with a common and well known form of mechanism by which the shaft is driven a definite number of revolutions by a driven belt 2 on the pulley 3, and then the belt is automatically shifted to the loose pulley 4, so that, as will hereinafter more fully appear, a definite number of stitches are formed by the stitch forming mechanism and then the belt 2 is shifted to the loose pulley, the stitch forming mechanism stops and a manual operation is then necessary to start the stitch forming mechanism again. This mechanism and method of operation are all well known and form no part of my invention.

The shaft 1, at the left hand end thereof, as viewed in Fig. 1, has an eccentric 5 attached thereto, best shown in Fig. 4. This eccentric is surrounded by and reciprocates the eccentric rod 6 which, at its upper end engages the arm of a crank 7 secured to the needle arm operating shaft.

The rotation of the shaft 1, rotates the cam 5, thus reciprocating the eccentric rod 6, and so oscillates crank 7 and needle arm operating shaft 8.

At the forward end of shaft 8, a needle operating arm 9 is secured to the shaft, as best shown in Fig. 7. The needle operating arm secures a curved needle 10, in any suitable or appropriate manner as by a screw 11.

Oscillation of shaft 8 causes needle 10 to oscillate from left to right and vice versa, as viewed in Fig. 7, just skimming the surface of a transverse groove 12 in needle plate 13, well shown in Figs. 5, 25 and 26.

Undue wear on needle plate 13 is obviated by causing the needle to rub most strongly against hardened wear plate 14, conveniently replaceable and held in place by any proper or convenient means, as by screw 15, screw-threaded into the needle plate 13, as shown in Figs. 5, 11 and 25.

The needle plate 13 is secured to transverse arm D by forming arms 14, 15 and 16 thereon, arm 14 being well shown in Fig. 4, and arms 15 and 16 in Figs. 3 and 7. Any proper or convenient means may be used to secure the arms 14, 15 and 16 to transverse arm D. I employ large head screws 17, 18 and 19.

The needle plate 13 is formed preferably of steel and is of a sufficient body to be relatively very stiff and unyielding so that pressure exerted thereagainst from below in positioning material or a button thereagainst in the operation of the machine will not cause displacement or distortion thereof.

The needle plate 13, as best shown in Fig. 5, is provided with an orifice 90. This orifice allows a portion of material, positioned below the needle plate to somewhat protrude above the plate into the path of the oscillating needle skimming the surface of the groove 12 so that the needle may pass into and then out of the material so protruding whereby, as will hereinafter more fully appear, the thread, carried by the needle, will follow a like path as the needle.

In order to position material to be sewed and material to which a button is to be sewed, together with the button, in proper relation to the needle plate and needle, I have provided a supporting means. This supporting means is particularly characterized by the fact that it is

strongly spring pressed upwardly, so that material supported thereby is pressed tightly against the under side of the needle plate, but is arranged to be manually depressable to afford an opportunity to easily position the material or work after which the material or work is then strongly pressed against the underside of the needle plate.

The immediate material, button or work support is the finger 20, well shown in Fig. 2. This finger is positioned below and centered substantially on the intersection of a centre line of groove 12 and a centre line of orifice 90 drawn substantially parallel to a long side of orifice 90.

Finger 20 is carried by arm 21, pivoted at 22 on the base C. On the under side of pivoted arm 21 is a wear plate 24 attached by any suitable or appropriate means to the pivoted arm 21, as by screw 25. This wear plate 24 rests on roller 26, attached revolvably by screw 27 to one arm 28 to a two arm crank journalled on screw 29, screw-threaded into the base C. The other arm 30 of the crank extends upwardly and is secured to one end of a spring 23. The other end of the spring 23 is attached to a screw-threaded link 31 passing through a bore in a projection 32 of the base C. The outer end 33 of link 31 is screw-threaded and is engaged by internally screw-threaded thumb nut 34. It is evident that the stress exerted by spring 23 may be increased or diminished by turning thumb nut 34 which bears against projection 32.

It is evident that the spring 23, operating on arm 30 causes the crank to have a tendency to rotate on 29 thus tending to move arm 28 and 26 upwardly and so arm 21 and finger 20, so that finger 20 may be biased toward needle plate 13 to any extent desired.

In order to limit the upward movement of finger 20 I provide a limiting stop therefor. From one side of pivoted arm 21, as best shown in Fig. 3, I drop a stop member 35 which is provided with a stop shoulder 36, perhaps best shown in Fig. 2. This stop shoulder lies in the path of a sector 37 pivoted at 38 on the base C. The sector also contacts adjustable rod 39 so that the upward tendency of stop shoulder 36 against sector 37, is resisted by sector 37 abutting rod 39. The rod 39 is screw-threaded into a projection 40 of the base C and may be adjusted longitudinally by turning thumb piece 41 and retained in adjusted position by spring-pressed tooth 42 engaging serrations in the periphery of thumb piece 41.

When, for the purpose of easily introducing work between the finger 20 and needle plate 13, it is desired to depress finger piece 28, then a downward pull is given to rod 43, well shown in Figs. 2 and 3. This, of course, may be operated by a foot pedal, not shown.

Work material, as textile material or the like to be held up by finger 20 should also have a further support for the material not directly contacted by 20, I provide such a support somewhat in the form of a table 44, well shown in Figs. 2 and 3 and in plan in Fig. 9. The table 44 is supported and secured in any proper or appropriate manner to swinging bracket 45. This swinging bracket 45 has two upwardly projecting arms, one 46, well shown in Fig. 2, and, the other 47, well shown in Fig. 3. Each of the projecting arms 46 and 47 is swingingly secured to transverse arm D by headed bolt 48, well shown in Fig. 2, on the threaded end of which is securing threaded nut 49, best shown in Fig. 3.

A spring 50 attached at one end to an eye 51 on

bracket 45 and at the other end to needle plate 13 biases bracket 45 and so table 44 upwardly toward needle plate 13. However, a slight pressure downward on table 44 suffices to lower it so that material may be inserted easily between the top surface of the table and the under surface of the needle plate. Furthermore, a spring 52, best shown in Fig. 2, is attached at one end to an eye on the underside of bracket 45 and at the other end to pivoted arm 21, and the relative stiffness of the springs 50 and 52 is so arranged that, 52 being the stiffer, when finger 20 is depressed by manipulating manually operating rod 43, the table 44 is simultaneously depressed so that placing material between the top of the table and the under side of the needle plate is facilitated.

I have illustrated a well known form of loop thrower in connection with the mechanism as shown in the drawings. This loop thrower has arm 53, best shown in Fig. 5, provided with two thread engaging fingers 54 and 55, best shown in Fig. 4, and thread groove 56 and thread shoulder 57. This loop thrower is adjustably attached, as by screw 58, to link 59. Link 59 is a continuation of link 60 with an interposed ball and socket supporting mechanism 61 and 62. The socket portion 62 is in two parts, one part 63 being removable and screw held to permit clasping of ball 61. The socket portion is rotatably supported on 64 which is eccentrically positioned on 65 so that by rotating 65 the loop throwing arm 53 may be raised or lowered to bring the fingers 54 and 55 closer to or farther away from the path of the needle 10. The eccentric is secured in adjusted position by blind set screw 66, best shown in Fig. 4. The link 60 extends to and is connected to a well known form of knuckle joint designated as a whole by K and best shown in Fig. 2. This joint K is attached to and operated by main shaft 1. When operated the knuckle joint moves loop thrower arm 53 endwise and also causes the finger end to oscillate describing an arc of a circle just above the work piece.

The thread 66 used by the machine, see Fig. 2, comes from any suitable source and passes first through an orifice 67 in an adjustable up and down and in and out guide 68, held in adjusted position by screw 69. From guide 68, the thread passes between and beneath the center of a pair of spring-pressed friction discs 70 and 71, well shown in Fig. 3. Then the thread passes through eye 72 attached to reciprocating rod 73. The thread then passes between and below the center of a pair of spring-pressed friction discs 74 and 75, best shown in Fig. 3, thence to guide eye 76, guide eyes 77 and 78 and to and through the eye of the needle 10 just back of the point thereof.

During the operation of the machine no change takes place in guide 68, the pair of discs 74 and 75, or guides 76, 77 or 78. However, shaft 8 has a cam 79 thereon, best shown in Fig. 15, this cam bears against rod 80. Rod 80 bears against disc 70 and when the high portion of cam 79 passes rod 80 it forces rod 80 and disc 70 against the compression of 81 to slightly separate friction discs 70 and 71 to thereby remove the major holding power of these discs on thread 66. This action occurs while the needle 10 is advancing in the direction of the arrow 82, Fig. 15, until about the instant the point of the needle reaches just beyond the center of the orifice in the needle plate.

The rod 73 carrying eye 72 passes through and is guided by orificed stud 83, best shown in Fig.

5, supported by transverse arm D. The lower end of rod 73, as best shown in Fig. 4, rests on arm 84 of a two arm crank, pivoted at 85 and having the other arm 86 resting on an eccentric 87 secured on shaft 1. The contact between arm 86 and eccentric is assured by spring 88 having one end attached to the transverse arm D and the other end attached to an extension 89 of the hub of arm 86.

10 As shaft 1 rotates and rotates eccentric 87 the rod 73 and so eye 72, is reciprocated up and down. The eye 73 is at about its maximum upper position when the needle 10 is at the extreme of its forward stroke. This motion of eye 72 tends to relieve tension thread 66 while the needle 10 is moving forward, but tends to hold more tension on the thread while the needle is returning.

15 The operation of my device in sewing a button to a material is well shown in Figs. 16 to 21 inclusive. For illustration I have selected a somewhat flat form of button 91 having a cloth center 92 protruding from one side thereof.

20 The first step in attaching a button to textile material, by the practice of my invention, is to first depress the finger 20 by operating the rod 43 by a pedal or otherwise. This depresses finger 20 and table 44 so that one may quite easily position a button 91 on finger 20 and then, folding the material 93 to which the button is to be attached so that the fold line 94 may be positioned adjacent the cloth protuberance 92 and both positioned to project somewhat within the orifice 90 of the needle plate 13 with the bulk of the material 93 resting upon table 44, the finger 20 is allowed to assume its biased position so that the button 91 and the material 93 assume the position as shown in Fig. 16. With the work piece in the position as shown in Fig. 16, and the needle 10 with the thread 66 passing through the eye of the needle and a substantial length protruding, then the machine is started by shifting the belt, in the well-known manner from the loose pulley 4 to the pulley 3. The needle 10 will start forward and pass through a portion of the material 93 and through the protuberance 92 of the button 91 and will arrive at the position as shown in Fig. 17. Meanwhile the loop thrower arm 53 moves forward into the position as shown in Fig. 17 to enter the loop 95 as the needle 10 starts back. The full forward motion of the loop thrower arm 53 is shown in Fig. 18. As the needle proceeds backwardly, the loop from the arm 53, in the well-known manner, moves into the position as shown in Fig. 19 and then rolls over to the position as shown in Fig. 20 so that the needle 10 advancing again can pass through the loop 95 and proceed forward into the material 93 and the protuberance 92 on the button 91 while the loop former arm 53 moves backwardly as shown in Fig. 21, to again move forwardly rolling over to the position as shown in Fig. 17 to protrude through the next loop as 95 formed by the advancing needle 10. These operations will be repeated a predetermined number of times and then, as hereinbefore stated, by well-known means, the main shaft 1 will cease rotating and the needle will cease oscillating. The thread is then properly cut and the whole operation is repeated after positioning another button and material as just hereinbefore described.

25 70 The material 93 and the button 91 when removed from in place as shown in Fig. 16, after the sewing has been completed will appear as shown in Fig. 22. When the material 93 is spread out flat removing the fold 94 and viewing the material from the side reverse from the button, the

appearance will be as shown in Fig. 23, that is, all stitches are shown in dotted lines to indicate that they do not appear upon the face of the goods opposite to where the button 91 is attached.

Buttons used for clothing are of various construction and various forms. The button 91, as shown in Fig. 16, is what might be called a flat form. Button 96, as shown in Fig. 28, is of a somewhat hemispherical form with a protruding textile material 97. The button 98, as shown in Fig. 27, is of a somewhat hemispherical form but with a metal eye 99 for attachment to material.

If a machine of my invention is to be used for attaching buttons such as 96 and 98 I prefer to form the finger 20 with a longitudinal orifice 100 therein, as shown in Fig. 24, and use an adapter 101 provided with a tang 102 for positioning in the bore 100. This adapter 101 is preferably formed with a concave upper face 103 shaped to more nearly perfectly contact the outside of a somewhat hemispherical button.

When sewing a button, such as 98, to material, I prefer to modify the needle plate to the form as indicated by 104 with a raised somewhat dome-shaped portion 105 in the center so that the eye 99 of a button 98 may project upwardly and fit into two notches 106 and 107 as shown in Fig. 25. The dome-shaped portion 105 will have slots therethrough as at 108 and 109 to allow the passage of the needle 10. This construction will allow the needle 10 to pass right through the eye 99 of the button 98 after passing into the material 93.

The machine of my invention is especially adapted for blind-stitch tacking, that is, sewing material together at separated points. In order to do this more successfully, I prefer to employ the tacking adapter designated as a whole by F and illustrated in perspective in Fig. 10 and shown in place in Figs. 8, 9 and 13.

My tacking adapter F comprises a lower portion 110 which extends upwardly within an upper portion 112 and passes through an orifice 113 in the top of 112 and protrudes as a tacking ridge 114. The lower portion 110 is provided with a finger operably threaded screw 115 by which the device may be attached to the finger 20 of my depressible support.

When I desire to do tacking, I position the tacking adapter F on the finger 20 as shown in Fig. 8, and as illustrated in section in Fig. 7. I place my adapter F on finger 20 in position so that when support 20 is allowed to move upwardly due to its bias, the tacking ridge 114 will protrude into the orifice 90 of the needle plate 13 to the desired extent. The adjustment 37 coacting with 39 controlling the bias, taking care of the amount the said tacking ridge 114 will protrude. The material to be tacked, as 116 in Fig. 13, is interposed, when finger 20 is depressed, between the tacking ridge 114 and the lower surface of the needle plate 13. When the material is so placed it is held strongly in adjusted position because, the upper portion 112 of adapter F presses strongly against the material at the two lips 117 and 118. This strong pressure is obtained by interposing springs 119 and 120 between the lower and upper portions of adapter F.

The tacking is accomplished by starting the machine in the usual manner and allowing it to make the predetermined number of stitches and then automatically stop, whereupon the material to be tacked is shifted to a new position and stitching resumed.

In Fig. 14 I have illustrated the tacking of a minor piece of material 121 to a major piece of material 122. The minor piece of material may be a label to be attached to a garment and it is desired to blind tack stitch the corners of the label to the garment. This could be done by my machine by arranging the materials as illustrated in Fig. 14. The completed work is as illustrated in Fig. 12. The stitches would show on the label side of the garment, but would not show on the opposite side of the garment.

Although I have particularly described a preferred physical embodiment of invention and modified form thereof, nevertheless, I desire to have it understood that the forms selected are merely illustrative, but do not exhaust the possible physical embodiments of the idea of means underlying my invention.

What I claim as new and desire to secure by Letters Patent is:

1. A sewing machine of the blind-stitch type for forming and applying stitches to a stationary work piece including a curved needle and a needle plate formed with an orifice transverse thereto, including, in combination, a support for a work piece positioned beneath the needle plate, a pivoted lever carrying the support whereby the support is reciprocable, and spring means to bias the pivoted lever in a direction such that the support will be biased toward the needle plate, a pivoted two arm crank, a spring, said spring having one end attached to a rigid support and the other end attached to one arm of the crank, a revolvable disc mounted on the other arm of said crank, said disc bearing against said lever on the side remote from the needle plate whereby the support is biased toward the needle plate.

2. A sewing machine of the blind-stitch type for forming and applying stitches to a stationary work piece including a curved needle and a needle plate formed with an orifice transverse thereto, including, in combination, a support for a work piece positioned beneath the needle plate, means supporting the support and adapted to allow the support to reciprocate toward and away from the needle plate, said support provided at its end adjacent the needle support with a longitudinal orifice therein, a button adapter formed with a projection fitting the said orifice and terminating at the outer end in a head formed with a depression adapted to correspond with and receive a specific button or the like.

3. A sewing machine of the blind-stitch type for forming and applying stitches to a stationary work piece including, an arm, a curved needle and a needle plate carried by the arm and formed with an orifice transverse to the needle, including, in combination, a work piece receiving table, said table pivotally mounted on the arm and in the same plane and adjacent to the needle plate, whereby it may approach toward and recede from the level of the lower face of the needle plate, spring means to bias the table toward the needle plate, a support for a work piece positioned beneath the needle plate, means supporting the support and adapted to allow the support to reciprocate toward and away from the needle plate.

4. A sewing machine of the blind-stitch type for forming and applying stitches to a stationary work piece including a curved needle and a needle plate formed with an orifice transverse thereto, including, in combination, a support for a work piece positioned beneath the needle plate, means supporting the support and adapted to allow the

support to reciprocate toward and away from the needle plate, spring means to bias the support toward the needle plate, a manually operable means for drawing the support away from the needle plate and means for limiting the movement of the support toward the needle plate, the last mentioned means including an abutment on the support, a sector having one somewhat radial face positioned in the path of said abutment and the other somewhat radial face positioned to be contacted by an adjusting means, a pivot for said sector and a rod mounted on a rigid support to project into the path of said sector and limit its movement in one direction and manual means to adjust said rod longitudinally and means for retaining said rod in adjusted position.

5. A sewing machine of the blind-stitch type for forming and applying stitches to a stationary work piece including a curved needle and a needle plate formed with an orifice transverse thereto, including, in combination, a support for a work piece positioned beneath the needle plate, means supporting the support and adapted to allow the support to reciprocate toward and away from the needle plate, a tacking fitting for attachment to said support, said fitting including a portion attached but removably secured directly to said support, said portion formed with a tacking ridge adapted to be positioned in the orifice of said needle plate and to receive and support the material to be tacked just below the tacking position, said fitting including another portion reciprocable longitudinally relative to the first mentioned portion, the two portions slideable one on the other, headed bolts passing through each restraining too great separation thereof, a spring between the portions and around the bolts biasing the portions apart, a work piece receiving face adjacent and surrounding the tacking rib and slightly lower whereby the work piece may be wedged between the work receiving face and the under side of the needle plate with the tacking rib supporting the work piece at the position of a particular tack.

6. A sewing machine of the blind-stitch type for forming and applying stitches to a stationary

work piece including a curved needle and a needle plate formed with an orifice transverse thereto, including, in combination, a support for a work piece positioned beneath the needle plate, means supporting the support and adapted to allow the support to reciprocate toward and away from the needle plate, said needle plate formed with an upwardly projecting portion forming a depression in its under side adapted to receive and seat a button, said projecting portion formed with a transverse needle groove and on a line at a right angle to the needle groove with eyelet button shank receiving notches, one on each side of the needle groove whereby an eyelet shank button resting on the support is positioned to receive thread therethrough from the needle.

7. A sewing machine of the blind stitch type for forming and applying stitches to a work piece, including, in combination, a curved needle and a needle plate formed with an orifice transverse thereto, a tacking fitting below the needle plate including two portions, one of said portions including a tacking ridge and the other of said portions including a work piece receiving face adjacent and surrounding the tacking ridge, said portions relatively reciprocable longitudinally, a spring resisting relative reciprocation of said portions, means for supporting and reciprocating said fitting toward and away from said needle plate whereby a work piece may be wedged between the work piece receiving face and the needle plate with the tacking ridge supporting the work piece at the position of a particular tack in the surface of the needle plate.
